UNITED STATES PATENT OFFICE

117,490

DESIGN FOR AN AUTOMOBILE RADIO SET OR THE LIKE

George W. Bill, Cincinnati, Ohio, assignor to The Crosley Corporation, Cincinnati, Ohio, a corporation of Ohio

Application February 2, 1939, Serial No. 82,737

Term of patent 7 years

To all whom it may concern:

Be it known that I, George W. Bill, a citizen of the United States and a resident of Cincinnati,
in the county of Hamilton and State of Ohio,
have invented a new, original, and ornamental
Design for an Automobile Radio Set or the like,
of which the following is a specification, reference being had to the accompanying drawing, forming a part thereof.

In the drawing:

Figure 1 is a perspective view of my novel
automobile radio set.

somewhat reduced scale.

The side of the radio set not shown is the same as the side shown in Figure 1.

I claim:

The ornamental design for an automobile radio set or the like, substantially as shown and described.

GEORGE W. BILL.
